[57] **CLAIM**

The ornamental design for a lamp head for an adjustable task light, as shown and described.

DESCRIPTION

FIG. 1 is a top perspective view of a lamp head for an adjustable task light showing my new design, the support arm and base being shown in broken lines for illustrative purposes only;

FIG. 2 is a front elevational view thereof on an enlarged scale;

FIG. 3 is a rear elevational view thereof on an enlarged scale;

FIG. 4 is a top plan view thereof on an enlarged scale;

FIG. 5 is a bottom plan view thereof on an enlarged scale;

FIG. 6 is a side elevational view thereof on an enlarged scale, the opposite side being a mirror image;

FIG. 7 is a bottom perspective view thereof on an enlarged scale;

FIG. 8 is a top plan view of a second embodiment of my new design;

FIG. 9 is a side elevational view thereof, the opposite side being a mirror image;

FIG. 10 is a bottom plan view thereof;

FIG. 11 is a front elevational view thereof; and

FIG. 12 is a rear elevational view thereof.
